UNITED STATES PATENT OFFICE.

WILLIAM M. KURTZ AND MILTON R. MAY, OF ATHENS, OHIO.

CLOSET-SEAT.

995,355.

Specification of Letters Patent. Patented June 13, 1911.

Application filed April 14, 1911. Serial No. 620,971.

To all whom it may concern:

Be it known that we, WILLIAM M. KURTZ and MILTON R. MAY, citizens of the United States, and residents of Athens, in the county 5 of Athens and State of Ohio, have invented certain new and useful Improvements in Closet-Seats, of which the following is a specification.

Our invention relates to water closet seats, 10 and more particularly to that kind of water closet seat comprising two sections separated from one another throughout their length. And it consists in the means hereinafter set forth whereby the seat sections are maintained in the desired separated relation to 15 each other to form a strong and stiff seat, and are hinged to the bowl, the pindle of the seat hinge constituting also, if desired, the pindle of the hinge which holds the seat 20 cover in place.

We will first describe in connection with the accompanying drawings the manner in which our improvements are or may be carried into effect, and will then point out more 25 particularly in the claims, those features of the same which we believe to be new and of our own invention.

In the accompanying drawings, Figure 1 is a perspective view of a portion of a water 30 closet bowl, with seat, seat cover and hinge embodying our invention in its preferred form. Fig. 2 is a rear elevation of the same. Fig. 3 is a plan of the same with the cover thrown back and partly broken away, 35 and a portion of the hinge and seat in section to better show the hinge construction. Fig. 4 is a similar view of a modification. Fig. 5 is a view of a modified form of hinge pindle.

40 Like letters of reference indicate corresponding parts in all the figures.

A A are the two seat sections separated from one another throughout their entire length. In the construction represented in 45 Figs. 1, 2 and 3, they are secured at their rear ends to a skeleton metallic brace frame B which is interposed between said rear ends and serves as a means to hold the seat sections at the desired interval apart, and in 50 the desired relation to one another to form a strong and durable seat. The metallic interposed frame to which the sections are secured is of sufficient length to give the requisite stiffness to the seat as a whole, 55 without rendering it necessary to connect the front ends of the same by a cross stay.

The frame at its rear end is cored out, as indicated at C, transversely of the seat, this tubular portion C being internally screw threaded to receive at opposite ends 60 the pindle sections D, on which the seat sections are hung. Each seat section has in its rear end a transverse hole for the passage of its appropriate pindle section D, which is screw threaded externally to engage the 65 internal thread in the tubular portion C of the frame which it is intended to enter. The end of the seat section is confined and clamped tightly between the head d of its pindle section and a shoulder c on the adjacent end of the tubular portion C of the frame B, a washer c' being preferably interposed between the shoulder c and the adjoining face of the seat section. The skeleton frame B, is attached furthermore to the seat sections, at points at or near the front of the frame by screws or bolts b' or their equivalents which bind tightly the frame to the sections at those points. The frame and seat sections and pindle sections are thus rigidly 70 attached to one another so as to move together as a unitary structure. The pindle sections are individually adjustable so that each may clamp its section independently of the other. This clamping action is desirable 75 in order to prevent the longitudinal splitting of the wooden seat sections, and also to avoid glue joints; and the independent clamping action is desirable in order that each seat section may be thus acted on, whenever the need arises, independently of the other. The use of the pindle sections separately screwing into opposite ends of the tubular part C of the frame, is convenient for 80 this purpose, but the same result could be 85 reached by making these pindle sections D in one with the frame B and providing nuts to screw upon their outer ends by means of which the seat sections could be independently clamped and acted on as in the 90 other case. This structural modification is illustrated in Fig. 5, and will be more particularly referred to in connection with the modified structure shown in Fig. 4. In this Fig. 4, the transverse tubular portion C of the frame B in the preceding 95 figures is alone retained, it having the form of an internally screw threaded cylindrical tube C', (corresponding to the part C in Figs. 1-3), into opposite ends of which the headed pindle sections D are screwed to 100 clamp and confine the ends of the seat sec- 105 110

tions mounted on them, all substantially as already represented and described in connection with Figs. 1-3.

Manifestly in lieu of having a pintle and separating or spacing device composed of a tube and two separate headed pintle sections or rods screwing into opposite ends of the tube, the tube and pintle sections could be made integral as represented in Fig. 5, where 10 the device consists of a pintle having a central portion C^x with shoulders c^x , pintle rods D^x extending in opposite directions from each end of the central portion outwardly from the shoulders c^x and on a prolongation 15 of one and the same axis, and clamping nuts n to screw upon the outer screw threaded ends of the parts D^x .

The other portion of the hinge by which the seat is connected to the bowl, consists of 20 two metallic brackets F , attached in any suitable or known manner to the bowl and having eyes f , which enter and fit slots g in the seat sections (Fig. 2) intersecting the passage in said seat sections, through which 25 the pintle rods or sections extend, said pintle rods passing through the eyes f .

The hinge for the cover H is conveniently provided by brackets h , secured to a base plate i attached to the cover, said brackets 30 being provided with eyes h' which fit upon and can turn on cylindrical portions of the central part C or C' , which forms the pintle for these eyes.

In case the frame B is dispensed with and 35 a mere tube or pipe C' is used for the central portion which intervenes between the two seat sections, the front ends of those sections may be connected by a suitable cross stay s , which will afford the necessary stiffness.

40 In all of the three different forms of pintle represented in the drawings, the shouldered central part, as for example C , Figs. 1-3, C' , Fig. 4, or C^x , Fig. 5, constitutes the device by which the seat sections 45 are spaced at the proper interval apart; the pintle rods extending from opposite ends of this shouldered central portion, are the rods on which the seat sections are mounted, and on which they are tightly clamped between 50 the shoulders on the central portion and the heads on the outer ends of the pintle rods, the clamping means being separately adjustable so that each end section may be clamped independently of the other, the 55 pintle constituting one part of a hinge for attaching the seat to the bowl, the other part of which hinge is composed of the brackets F , and the whole structure—consisting of the pintle with its central spacing 60 portion, and the two seat sections—forming when properly secured together a strong, stiff and practically unitary structure, with

capacity for adjusting the clamping means to tighten their grip whenever needed, upon the ends of the seat sections held between 65 them respectively.

Having described our improvements and the best way now known to us of carrying the same into effect, we state in conclusion that we do not limit ourselves strictly to the 70 structure details hereinbefore described and illustrated, since manifestly the same can be varied to some extent without departure from the spirit of our invention: but

What we claim herein as new and desire 75 to secure by Letters Patent is as follows:

1. A water closet seat having two seat sections separate from one another throughout their length, a pintle constituting the pintle of the hinge by which the seat is 80 united to the water closet, and comprising a shouldered central portion by which the two seat sections are spaced at the desired interval apart, pintle sections or rods extending from opposite ends of the shouldered central portion, on which the seat sections are mounted, and clamping means at the outer extremities of the pintle rods between which and the shouldered central portion of the pintle, the seat sections are 85 severally tightly pressed and held, said clamping means being independently adjustable for the purpose of regulating the clamping action upon their respective seat sections as desired substantially as hereinbefore set forth.

2. A water closet seat having two seat sections separated from one another throughout their entire length, a metallic frame B interposed between and secured to the rear 100 ends of the seat sections, and serving to space them at the proper interval apart and to brace and stiffen them in that separated position, a central shouldered transverse portion C at the rear end of the frame B , pintle 105 rods extending from opposite ends of said central portion on which the seat sections are respectively mounted, and clamping means at the outer extremities of the pintle rods, between which and the shouldered 110 central portion the seat sections are severally tightly pressed and held, said clamping means being independently adjustable for the purpose of regulating the clamping action upon their respective seat sections as 115 desired, substantially as hereinbefore set forth.

In testimony whereof we affix our signatures in presence of two witnesses.

WILLIAM M. KURTZ.
MILTON R. MAY.
